UNITED STATES PATENT OFFICE.

EGERTON W. KIBBEY, OF MINNEAPOLIS, MINNESOTA.

POST.

Application filed March 10, 1925. Serial No. 14,446.

My invention relates to improvements in posts, particularly though not exclusively, for wire rope guard rails for highways.

An object of the invention is to provide 5 a relatively inexpensive post of the present nature, the same being capable of withstanding heavy strains and adapted to resist the deteriorating effects of the elements for an indefinitely long period.

10 Another object is to supply a composite post of the instant type that is readily adapted for construction in the process of the erection of a rope guard rail.

15 A further object is to produce a post including a casing and a core of concrete, the casing not only supplying a protecting jacket for the concrete and lending strength thereto, but providing the form for the molding of said concrete core.

20 Another object is to provide a composite post of the present type, wherein provision is made for the contraction and expansion of the concrete core.

25 An additional object of the invention is to provide an improved method for making a guide rail post, wherein different steps in the construction of the post are co-ordinated to advantage with certain phases in the erection of the guard rail structure.

30 With the foregoing and other objects in view, which will appear in the following description, the invention resides in the novel combination and arrangement of parts and in the details of construction herein- 35 after described and claimed.

In the drawings, Fig. 1 is a perspective view illustrating a number of posts embodying my invention and put to use in a guard rail structure; Fig. 2 is a view of one of 40 said posts, the lower portion thereof being shown in section and the upper portion in elevation; Fig. 3 is a detail longitudinal sectional view of the upper portion of said post; Fig. 4 is a transverse sectional view 45 taken on the line 4—4 of Fig. 3; Fig. 5 is a view partly in section and partly in elevation, the same illustrating the upper end of a post embodying my invention and showing, particularly, an alternate form of cap 50 therefor; Fig. 6 is a transverse sectional view taken on the line 6—6 of Fig. 5 and Fig. 7 is a transverse sectional view of an alternate form of post embodying my invention.

55 Referring to the drawings, it will be understood that my invention embodies a post (Fig. 2) including a permanent casing 10

and core 11 of concrete therein. This composite post is preferably made in conjunction with the erection of a guard rail structure of which said post is a part. The casing 10 is of asbestos-wood or other suitable composition that is proof against fire, decay and like deterioration by the elements, and which has those qualities that lend reinforcement to the core 11. This casing 11 is 60 planted in a post hole (Fig. 2), the upper end of said casing being equipped with a rope supporting hook 12 of ordinary pattern. The shank 12^a of the hook 12 is passed through diametrically opposed openings 13 65 in the casing 10. The head of the hook 12 receives a wire rope, as at 14. The threaded end of the shank 12^a takes a nut 15, which, when turned against a washer 16 abutting the casing 10, causes the tip of the head 70 of the hook 12 to be drawn flush with the casing 10 and thereby secure the rope 14 against dislodgment from said hook 12. The casing 10, planted in its permanent position 75 in a post hole provides a mold into which concrete, constituting the core 11, is poured. In this connection it will be observed that the concrete 11 stops short of the upper edge of the casing 10 and that a different 80 material is employed to fill and cap said casing. This capping material may be of cement or other suitable substance capable of being molded in the casing and shaped over the upper edge thereof to form a cap 85 17 to keep the interior of the post dry and thereby protect the concrete core 11 and the inner portion of the casing 10. After the concrete core 11 has become set, the rope 14 is tightened through the medium of the usual anchoring devices and the guard is complete. 90 Having performed its use as a mold, plugged at the bottom and supported by the earth about it during the pouring process, the casing 10 provides a permanent protective jacket for the concrete core 11, said 95 jacket being capable of indefinitely long wear and serving as an effective reinforcement for the core 11 under such strains as may be directed against the post.

The casing 10 may have a split joint as at 105 10^a reaching longitudinally thereof. Thus split, the casing 10 accommodates for expansion and contraction of the core 11. And further provision for expansion may be made by pouring the concrete core 11 about 110 a temporary core strip (not shown) held radially of the casing 10, then withdrawing

said core strip before the concrete becomes hard and thereafter filling the formed segmental cavity with pitch or other non-hardening material to provide an expansion core-section 11^a. Of course, this core-section 11^a is offset from the joint 10^a in the casing 10 to insure the retention of the expansion material.

The hook 12 is arranged with the shank 10 12^a thereof intersecting the diametrical plane of the split joint 10^a in the casing 10 to keep said casing from spreading not only when the concrete core 11 is being poured, but after that time, as well. A crown 18 (Fig. 18 5) designed to encompass the top of the casing 10 may be used to protect the core 11 and to keep the casing 10 from spreading at the joint 10^a. Said crown 18 may be sealed to the top of the post by the cement 20 cap 17, which serves as a container for the cement in its application to the top of the post.

Changes in the specific form of my invention, as herein disclosed, may be made within 25 in the scope of what is claimed without departing from the spirit of my invention.

Having described my invention, what I claim as new and desire to protect by Letters Patent is:

- 30 1. A post including a concrete core, a permanent core reinforcing casing in which said core is molded, said casing having a split joint extending longitudinally thereof, a tie member reaching transversely through opposite sides of the casing and intersecting the diametrical plane of said joint.
- 35 2. A post including a core, a permanent core reinforcing casing in which said core is cast, a part of said core being of concrete material and another part thereof of material incapable of hardening, said latter part comprising a relatively small segment of the

core, said casing having a split joint extending longitudinally thereof and offset from the non-hardening core segment.

45 3. A post including a core, a permanent core reinforcing casing in which said core is cast, a part of said core being of concrete material and another part thereof of material incapable of hardening, said latter part 50 comprising a relatively small segment of the core, said casing having a split joint extending longitudinally thereof, and a tie member reaching through opposite sides of the casing and intersecting the diametrical plane of said joint.

55 4. A post including a concrete core, a permanent core reinforcing casing having a split joint extending longitudinally thereof, and a tie member reaching transversely 60 through opposite sides of the casing and intersecting the diametrical plane of said joint, said casing comprising a mold in which the core is cast about said tie member.

65 5. A post including a concrete core, a permanent core reinforcing casing in which said core is cast, said casing having a split joint extending longitudinally thereof, a crown for the casing adapted to keep the same from 70 spreading, and a tie member extended through opposite sides of said casing, said member serving also to keep said casing from spreading.

75 6. A post comprising a concrete core having a radial slit along one side and a permanent core reinforcing casing surrounding said core, said casing having a slit at a locality out of register with said core split, and means for holding said casing in close en- 80 circling position about said core.

In testimony whereof, I have signed my name to this specification.

EGERTON W. KIBBEY.
